UNITED STATES PATENT OFFICE.

ARVIN C. WEBSTER, OF DETROIT, MICHIGAN.

SPRING SHACKLE AND METHOD OF FORMING THE SAME.

Application filed April 30, 1920. Serial No. 377,941.

To all whom it may concern:

Be it known that I, ARVIN C. WEBSTER, a citizen of the United States of America, residing at Detroit, in the county of Wayne 5 and State of Michigan, have invented certain new and useful Improvements in Spring Shackles and Methods of Forming the Same, of which the following is a specification, reference being had therein to the accompanying drawings.

The invention relates to the manufacture of spring shackles, spring clips, etc., and it is the object of the invention to increase the strength and to cheapen the manufacturing cost, as hereinafter set forth.

In the drawings:

Figure 1 is an elevation of the blank from which the shackle is formed;

Figure 2 is a similar view showing a portion of the blank after the threading operation;

Figure 3 is a view showing the blank after the first bending operation;

Figure 4 is a similar view showing the re-fashioned blank;

Figure 5 is a view similar to Figure 4, showing a modified construction designed for use as a spring clip.

In the construction of spring shackles, 30 it is usual to provide two parallelly arranged pivot bolts connected to each other by bifurcated links and respectively engaged with the spring and the supporting or supported member. To permit of assembling and dismounting at least one of the links must be removable and securing means must be provided for this removable link.

With the present invention the parallel pivot pins are formed from an integral blank, 40 the opposite ends of which are threaded and the threading operation is preferably formed by rolling prior to the initial bending of the blank. In the process of manufacture the first bending of the blank is into a U-shaped form, but in a subsequent operation this form is re-fashioned to produce a substantially straight connecting link portion.

In detail, A is a blank formed of straight round bar stock having end portions B 50 and B' reduced in diameter and threaded. This thread is preferably accomplished by a rolling process and the blank is first re-

duced in diameter, as indicated at C, to compensate for the enlargement produced by displacement of metal from the groove of the thread during the rolling process. Preferably the blank is first reduced in diameter to form the shoulder D and shank portion D' and this shank portion is then further reduced to form the portion C on which the threads are rolled. After the completion of the rolling of the threads, indicated at C', the external diameter thereof will correspond with the shank portion D', as indicated in Figure 2. The blank is then bent 60 into a U-shaped form, as indicated in Figure 3. It is then placed in dies and swaged or re-fashioned to form of the bend a substantially straight link portion E having a longitudinal projection upon one side thereof and intermediate its ends to strengthen the same the pivot pins F and F' projecting therefrom in parallel relation to each other. The portion E when re-fashioned is enlarged transversely to the axis of the 70 pins F and F' so as to form projecting shoulders.

In Figure 5 the construction is similar to that in Figure 4 with the exception that the design is one adapted for use as a spring 80 clip.

What I claim as my invention is:

1. A spring shackle comprising a cold swaged member having parallel pin portions and a connecting link portion.

2. A spring shackle comprising a cold swaged member having parallel pin portions, a connecting link portion and rolled threads on the pin portions.

3. A spring shackle formed from a single 90 piece of bendable material comprising a substantially straight link portion having a longitudinal projection upon one side thereof and intermediate its ends, and a pair of enlarged parallel cylindrical pin portions extending from the opposite side of the link portion adjacent to the opposite ends thereof, said pin portions having reduced shank portions intermediate their ends and terminating in reduced rolled threaded portions.

In testimony whereof I affix my signature.

ARVIN C. WEBSTER.
